UNITED STATES PATENT OFFICE.

CHARLES HENRY GUNTHORPE, OF BEAUMONT, TEXAS.

LIGHTNING-PROTECTING SYSTEM FOR OIL-TANKS.

1,175,749.

Specification of Letters Patent. Patented Mar. 14, 1916.

Application filed September 23, 1914. Serial No. 863,107.

To all whom it may concern:

Be it known that I, CHARLES H. GUNTHORPE, a citizen of the United States, and a resident of Beaumont, in the county of Jefferson and State of Texas, have made certain new and useful Improvements in Lightning - Protecting Systems for Oil-Tanks, of which the following is a specification.

10 This invention relates to a system for protecting oil tanks or allied analogous structures from damage and destruction by lightning.

An object of the present invention is to 15 provide a system by means of which there will be no likelihood nor danger of a spark occurring within an oil tank even should it be struck by lightning.

A further object is to provide a system 20 wherein the various plates which go to make up an oil tank are brought into good electrical connection one with the other and properly grounded.

A further object is to provide a system 25 which may be installed upon oil tanks already in use and at a minimum expense and by means of which all parts of the tanks are in good electrical connection so that substantially no resistance or air gaps will be 30 interposed in the path of a lightning discharge, should it strike any part of the tank, thus eliminating the possibility of a spark occurring within the tank and thus obviating the chances of explosion of the inflammable materials contained therein.

In the drawings accompanying this specification and forming a part thereof the preferable form of my invention is illustrated, in which:—

40 Figure 1 is a perspective view of an oil tank equipped with my lightning protecting system, Fig. 2 is an enlarged view in perspective of a portion of an oil tank illustrating the manner in which the various metallic plates are electrically connected and grounded, Fig. 3 is a sectional view taken 45 through one of the tank plates and the connector connected to a conducting circuit and grounded, the connector being also adapted 50 to hold in place the conducting wire which communicates therewith.

Referring to the drawings in which similar reference characters designate corresponding parts of the several views, the tank 55 illustrated in Fig. 1 is of that type designed to store oil therein and is made up of

a plurality of metallic segments or plates 4 which are riveted or suitably joined together in the ordinary way. It has been found in practice and by actual measurements that 60 considerable ohmic resistance may occur between two plates even though they be jointed together in a liquid tight manner. The plates being exposed to the action of the oil within the tank gradually acquire a film or 65 layer between the plates which although aiding the plates in defining a liquid tight receptacle materially hinder a flow of electricity between the plates such as would occur when the tank is struck by lightning. 70 This is the cause of sparks within the tank and the resulting explosion and tank destruction. In order to do away with this ever present danger of tank destruction I rigidly bond to each and every plate a connector 5, the same being illustrated in Fig. 75 3 as being secured thereto by the screws 6 which extend, for a limited distance only, into the metal plates and thus maintain a good electrical connection therewith. It is 80 to be understood, however, that the connector may be welded, soldered, or in other ways secured to the plates so as to effect a permanent and highly efficient connection therewith. The connector in addition to including the elongated base 7 through which the bonding screws 6 extend has the outstanding head 8 provided with the channel 85 9 extending along its face.

A plurality of encompassing cables 10 extend around the tank and are seated within the channels of the connectors 5 and effect an electrical connection therewith. Thus the plates of each horizontal row will be brought into proper electrical connection, 95 and the connecting of the horizontal conductors 10 is effected by the vertical extending conductors 11 which are welded or in other ways properly connected thereto. The vertically extending conductors 11 project 100 over the roof of the tank and meet at a central point 12 thereabove.

The roof plates are electrically connected together in a manner similar to the foregoing and by means of the vertical conductors 11 are brought into proper electrical connection with the plates forming the side walls of the tank. Thus it will be apparent that each and every plate constituting or making up the tank is electrically connected 110 to every fellow plate. The encompassing conductors 10 reinforce and strengthen the

tank as well as protect the same against lightning and local electrolysis.

A pair of aerials or lightning arresters 13 are located upon opposite sides of the tank 5 and are connected to the various tank conductors by means of the bars 14. The aerials are grounded, as at 15, which also applies to the vertical conductors 11 before mentioned. The roof plates in ordinary tank construction are usually nailed upon a wooden supporting structure and are rarely if ever in a good electrical connection with the sides of the tank. The present system not only electrically connects the various roof plates, but 10 brings them into electrical connection with the various side plates and the ground. A good electrical circuit will thus be provided for the lightning regardless of which particular plate is struck and all danger of 15

sparks which would ignite the tank contents 20 due to a path of high ohmic resistance is obviated.

Having thus fully described my invention, what I claim is:—

The combination with an oil tank of 25 metallic plate formation, of a plurality of connectors each including a flaring base and outstanding channel head electrically connected to each and every plate of the tank, a plurality of horizontally extending 30 encompassing conductors seated within the channels of said connectors and effecting electrical connections therewith, lightning arresters at the sides of the tank and in electrical connection with the ground and the electrical conductors mounted upon the tank.

CHARLES HENRY GUNTHORPE.
